UNITED STATES PATENT OFFICE.

WILLARD I. LEWIS, OF WALPOLE, MASSACHUSETTS.

AUTOMATIC WEB-GUIDING DEVICE.

1,136,686.

Specification of Letters Patent. Patented Apr. 20, 1915.

Application filed February 13, 1911. Serial No. 608,449.

To all whom it may concern:

Be it known that I, WILLARD I. LEWIS, a citizen of the United States, residing at Walpole, in the county of Norfolk, State of Massachusetts, have invented a certain new and useful Improvement in Automatic Web-Guiding Devices, of which the following is a specification, reference being had therein to the accompanying drawings.

10 The invention has relation to devices of the class intended to cause the selvages or margins of a traveling continuous web to follow along certain predetermined paths. Instances of such devices are shown, described, and claimed in my prior U. S. Letters Patent No. 678,121, granted July 9, 1901, and No. 905,720, granted December 1, 1908.

15 The invention consists essentially in the combination with traveling endless carriers acting to positively hold the selvage or margin of a web, of means for bringing the receiving portion of such carrying means automatically to the position of the oncoming portion of the selvage or margin, or to that of a predetermined lateral portion of the web, compensating thereby for variations in the line of travel of the said selvage or margin, or said other portion, of 20 the web.

An embodiment of the invention in practical form is shown in the drawings combined with a calendering machine.

In the drawings,—Figure 1 shows in side elevation the said calendering-machine and the said embodiment of the invention. Fig. 2 is a plan of the parts shown in Fig. 1, with certain parts broken away at one side of the machine. Fig. 3 is a view in vertical section in the plane indicated by the dotted line 3, 3, in Fig. 2.

The drawings show the frame 1 and calendering-rolls 2, 3, 4, of a calendering-machine of ordinary character and mode of 45 operation.

50 5 is the supply-roll of the web *a* to be operated upon in the machine, the said web passing from the roll 5 under and partly around a lower guide-roll 6, then up to, over, and partly around an upper guide-roll 7, then over and under the successive sectional spreader-rolls 8, 8, then to the automatic web-guiding devices which will 55 presently be explained, and from the latter to the calendering-rolls 2, 3 and 4, and from these last to the roll on which the calen-

dered web is wound; the roll last mentioned not being shown.

As a part of the automatic web-guiding devices, and as the controlling means therefor, I employ suitable means for detecting the positions of the respective selvages or margins of the web. For this purpose I preferably employ at 9 a detector-roll and co-operating parts and features embodying the main principles of the detector-rolls and the adjuncts thereof as shown and described in my prior Letters Patent aforesaid. The web passes under and partly around the detector-roll 9 after leaving the spreader-rolls 8, 8. As in the said patents, the said detector-roll is provided with radially movable detector-pins which are indicated by the dots at 10 in Fig. 2 of the drawings hereof, the said detector-pins acting to determine the position of sleeves 11, 11, lengthwise upon the shaft 12 of the detector-roll. As will be understood, the positions of the said sleeves 11, 11, are varied transversely of the machine in correspondence with variations in the positions of the respective selvages or margins of the web *a*, this variation being brought about through the agency of the detector-pins 10 according as the latter are controlled by the said selvages or margins. As the details of the detector-mechanism are fully shown and described in the said Letters Patent they are not shown herein, and specific description of the same is unnecessary. The detector-roll is rotated positively by means of driving connections comprising a sprocket-wheel 13 which is fixed upon the shaft 12, a sprocket-chain 14 passing partly around the said sprocket-wheel 13, a second sprocket-wheel 15, partly around which the said sprocket-chain 14 passes, a shaft 16 on which the said sprocket-wheel 15 is fixed, a second sprocket-wheel 17 fixed on the said shaft 16, a sprocket-chain 18 passing partly around the said sprocket-wheel 17, and a sprocket-wheel 19 fixed on one journal of the calender-roll 3, the sprocket-chain 18 passing partly around said sprocket-wheel 19.

Intermediate the detector-roll and the calender-rolls I employ the moving or traveling endless carriers to which I have referred. The essential features of the illustrated form thereof comprise selvage-carrying wheels 20, one of which is located at each side of the path of the traveling web,

and upon which the selvage or marginal portions of the web are received as the web leaves the detector-roll, and endless flexible bands, belts, or chains 21 which clamp the said selvage or marginal portions of the web upon the peripheries of the wheels 20. Each wheel 20 is journaled upon a stud 22 carried by a support 23, upon which stud the wheel is capable of revolving as the web travels onward. The corresponding flexible band, belt, or chain 21 travels upon flanged wheels or pulleys 24, 25, and 26 mounted in connection with said support 23, in addition to traveling around end-portions of a telescoping cylinder 27 and of a guide-roll 28, the said cylinder and cylinder-roll being mounted independently of the said support at the delivery-side of the carrier-devices. Between the guide-wheel or pulley 26 and the cylinder 27 the said band, belt, or chain extends around and coacts with about one-half of the periphery of the wheel 20. By means of this portion of the said band, belt, or chain the corresponding selvage or marginal portion of the web as it passes from detector-roll 9 to and around such part of the periphery of wheel 20 is gripped positively against the said periphery, and thereby firmly held. Wheels or pulleys 24 and 25 are made adjustable to enable the tension of the band, belt, or chain 21 to be regulated, and any slack thereof taken up.

The adjustability is attained by mounting them upon opposite arms of a supporting lever 29 which is pivoted at 30 upon the support 23. To one arm of the said lever is connected pivotally a screw-threaded rod 31 engaging with one internally-threaded portion of a swivel-nut 32, the other internally-threaded portion of the latter being engaged with a second screw-threaded rod 33 which is also pivotally connected at 34 with the lower portion of support 23. The screw-threads of rods 31, 33, are oppositely inclined. By turning the swivel-nut, the lever 29 and wheels or pulleys 24, 25, may be moved to tighten or slacken the band, belt, or chain 21 as required. The said wheels or pulleys are located respectively at opposite sides of the said band, belt, or chain so as to act the more readily and effectively in tightening or slackening the latter.

The supports 23 are pivoted at the delivery side of the carrier-wheels upon upper and lower pivots 35, 35. The axes of the pivots of each support are in practically the same vertical line as the delivery-point of the corresponding wheel 20, so that when the support is swung transversely of the machine upon the said pivots by the automatic adjusting mechanism the position of the said delivery-point is not disturbed transversely. The selvage or margin of the web leaves the periphery of the wheel 20 with the band,

belt, or chain 21, and with the latter passes under and partly around the telescoping cylinder 27, and passes thence to the calendering rolls.

The automatic adjustment of the receiving portions of the traveling carrying means transversely to the position of the selvages or margins, or other predetermined portions of the width of the web, is provided for by furnishing the longitudinally shifting sleeves 11, 11, of the detector-roll with arms 36, the outer portions of which are supported by a cross-rod 37 mounted in the supporting frame 38 for the detector-roll and adjacent parts. The said outer portions of arm 36 are forked to fit the said cross-rod, and are adapted to slide thereon transversely of the machine.

Each arm 36 is embraced by a fork 39 extending down from a portion 40 of support 23. Thereby, the movement of the corresponding sleeve 11 transversely of the machine occurring in the detecting action of the detector-devices operates through the engagement of the arm 36 with the said fork to shift the receiving portion of the traveling carrier-devices correspondingly.

At 11^a, Fig. 2, is shown a contracting spiral spring having its extremities engaged with the studs carried by the swinging supports 23, 23, and on which the wheels 26, 26, are mounted. This spring operates with a tendency to draw the carrier devices at the opposite sides of the machine toward each other, and through the engagement of the supports 23, 23, with the sleeves 11, 11, it operates to move the latter inwardly for co-action with the detecting pins 10.

As disclosed in the Letters Patent aforesaid, the detector-roll and associated parts are adjustable to suit the width of web operated upon. The distance apart, transversely of the machine, of the delivery-portions of the traveling carrier-devices is adjustable to suit the width of the web, and also to give the required spreading or transverse stretching action. To provide for the latter adjustment, the pivots 35, 35, are mounted upon blocks 41, 41, which in turn are mounted upon transversely-extending rods 42, 42, that are supported in bearings in stands 43, 43, attached to the frame 1 of the calendering machine. Each rod 42 is formed with right-and-left screw-threads, and each block 41 is internally threaded for screw-thread engagement with the portion of rod upon which it is fitted. Consequently, by rotating a rod, the opposite blocks thereon are moved nearer together or farther apart. The two rods are connected to rotate in unison by means of sprocket-wheels 45, 45, fixed thereon, and a sprocket-chain 46 passing around such sprocket-wheels, a hand-wheel 47 being fixed upon the upper rod for convenience in turn-

ing the rods when required. In the transverse adjustment of the delivery-portions of the carrier-devices, they take with them the end-sections of the telescoping roll 27.

5 When operating upon a web having selvages or margins which are thicker than other portions of the web, the thick portions mass up more quickly upon the receiving roll than the other portions. To enable the 10 increase to be distributed more or less I provide for shifting the guiding devices bodily transversely of the machine. This provision is made by giving the screw-threaded rods 42, 42, capacity for movement 15 endwise within their bearings in the stands 43, 43, and by supplying a convenient handle 48 Figs. 2 and 3 in connection with a hub 49 Fig. 2 having a projection 50 entering between shoulders on a block 51 mounted loosely on the outer portion of one of 20 such rods between collars 52, 52. The hub 49 is mounted upon an upright stud 53 carried by a bracket 54 projecting from one of the stands 43. By taking hold of the handle 25 48 and swinging the same and the hub 49 transversely, the screw-threaded rods and the delivery-portions of the carriers are shifted transversely, producing a corresponding shift of the web as it passes from 30 the carrier-devices. To lock the parts in the position of transverse adjustment which has been given to them, the handle 48 is connected with the hub 49 by a horizontal pivot 55 on which it is adapted to swing vertically, and a segmental rack 56 is fixed to 35 bracket 54 below the handle. A projecting portion of the handle is adapted to engage with the teeth of this rack, when the handle is in its normal lowered position. Thereby 40 the handle and other parts are locked against transverse movement. When the handle is raised, it is thereby disengaged from the rack, and may be swung transversely to the extent required for the transverse shift desired in the case of the 45 delivery portions of the carrier-devices, and then on lowering the handle into engagement with the segmental rack the parts are locked again.

50 Intermediate the two sets of carrier-devices I employ a cloth-support 60 Fig. 3 in the form of an arch. This cloth-support is telescopic, being made in overlapping sections as shown in Fig. 3 in section. Each 55 section is mounted upon an arched support 61, which is pivotally connected at 62, at the side adjacent the detector-roll, to a supporting stand 63 which is mounted upon the cross-rod 37 with capacity to be shifted 60 thereon transversely of the machine. This adjustment is effected by sliding the said stand along the said cross-rod. The stand is capable of turning around the cross-rod. A rearward extension of the stand 63 is 65 supported by an adjacent cross-rod 64 car-

ried by the fixed frame 38. For the purpose of enabling the arch-shaped support to be adjusted forwardly and rearwardly when required, an adjusting screw 65 is combined with the said rearward extension 70 of the supporting frame 63, the said adjusting-screw taking against the last-mentioned cross-rod. By turning the said adjusting-screw, the supporting-frame is rocked around the cross-rod 37, and thereby the 75 pivot 62, and with it the arch, is shifted forward or back, according as the adjusting-screw is turned in one direction or the other. To enable the height of the arch to be adjusted, an extension of the arched support 80 61 is furnished with an adjusting-screw 66 taking against the rearmost portion of the said supporting frame, 63. By turning the said adjusting-screw 66 in one direction or the other, the arch is swung 85 up or down. These different adjustments enable the arch to be brought into substantial concentricity with the traveling carrier-wheels 20.

In my co-pending application filed simultaneously herewith, Serial No. 608,448, I have claimed more broadly the combination comprising selvage detecting means, separate moving or traveling carriers for the respective selvages or margins of a web, and 90 swinging supports for the said carriers operatively controlled by the said detecting means to adjust the receiving portions of the said carriers to correspond with the oncoming portions of the selvages or margins. 95

I claim as my invention:

1. In combination, traveling endless carriers acting to positively hold the selvage or margin of a web, and means for bringing 105 the receiving portions of such carriers automatically to the position of the oncoming portion of the selvage or margin or to that of a predetermined lateral portion of the web, compensating thereby for variations in 110 the line of travel of the said selvage or margin, or other portion, of the web.

2. In combination, selvage - detecting means, selvage-carrying wheels and selvage-retaining endless bands coöperating with the 115 said wheels, and means controlled by the said selvage-detecting means for automatically adjusting the receiving portions of the said wheels and bands to correspond with the oncoming portions of the selvages 120 or margins of the web being operated upon.

3. In combination, selvage - detecting means, selvage-carrying wheels and selvage-retaining endless bands coöperating with the 125 said wheels, supports for the said wheels and bands pivotally mounted adjacent the delivery portions thereof, and means controlled by the said selvage-detecting means for automatically adjusting the receiving portions of the said wheels and bands to 130

correspond with the oncoming portions of the selvages or margins of the web being operated upon.

4. In combination, selvage-carrying means, for the opposite selvages of a traveling web, and means for bodily shifting the said means transversely at will without varying the distance apart of the devices at the opposite selvages to thereby correspondingly shift the general path of the web being operated upon.

5. In combination, selvage-carrying wheels and selvage-retaining endless bands coöperating with the said wheels, and means for bodily shifting the said wheels transversely without varying their distance apart to thereby correspondingly shift the general path of the web being operated upon.

6. In combination, selvage-carrying wheels and selvage-retaining endless bands coöperating with the said wheels, means for adjusting the said wheels toward and from each other, a telescoping arch-shaped web-support intermediate the said wheels, and means for adjusting the said web-support vertically and also from front to rear to bring it into concentricity with the wheels.

7. In combination, selvage-carrying wheels and selvage-retaining endless bands coöperating with the said wheels, swinging

supports for the said wheels and bands, supports to which the said swinging supports are pivotally hung, means to adjust the said supports transversely to thereby vary the distance between the delivery portions of the respective wheels, and means to shift the entire assemblage transversely with respect to the path of the web being operated upon.

8. In combination, selvage-detecting means, selvage-carrying means and selvage-retaining endless bands coöperating with the said wheels, swinging supports for the said wheels and bands pivotally mounted adjacent the delivery portions thereof, means controlled by the said selvage detecting means for automatically adjusting the receiving portions of the said wheels and bands to correspond with the oncoming portions of the selvages or margins of the web being operated upon, and means for bodily moving the delivery portions of the said wheels and bands and their swinging supports to effect a transverse shift of the general path of the web being operated upon.

In testimony whereof I affix my signature in presence of two witnesses.

WILLARD I. LEWIS.

Correction in Letters Patent No. 1,136,686.

It is hereby certified that in Letters Patent No. 1,136,686, granted April 20, 1915, upon the application of Willard I. Lewis, of Walpole, Massachusetts, for an improvement in "Automatic Web-Guiding Devices," an error appears in the printed specification requiring correction as follows: Page 4, line 40, for the word "means" second occurrence, read *wheels*; and that the said Letters Patent should be read with this correction therein that the same may conform to the record of the case in the Patent Office.

Signed and sealed this 11th day of May, A. D., 1915.

[SEAL.]

R. F. WHITEHEAD,

Acting Commissioner of Patents.
